NEEDLE LUBRICATING MECHANISM

Harold Ernest Elliott, Leicester, England, assignor to United Shoe Machinery Corporation, Paterson, N. J., a corporation of New Jersey

Application December 5, 1934, Serial No. 756,103
In Great Britain March 9, 1934

6 Claims. (Cl. 112—43)

This invention relates to sewing machines and is particularly, but by no means exclusively, concerned with sewing machines for operating on thick stubborn materials, such as leather.

5 In the boot and shoe manufacturing industry sewing machines are used to unite the sole of a welted boot or shoe to its welt by stitches passing through the sole and the welt, and oiling devices have been provided for oiling the needle of such 10 machines. In providing for the oiling of the needle it is very essential that just sufficient oil shall be supplied to keep the needle lubricated when the machine starts to operate and during the operation of the machine. If too little oil is 15 supplied to the needle, the needle is apt to be broken, and if too much oil is supplied, the oil is apt to splash on to and damage the work.

It is also desirable that the needle shall be lubricated when the machine stops so that during 20 the time that the machine is standing idle any sticky matter on the needle shall, as far as possible, be prevented from becoming hard and causing the needle to stick in the needle guide and be broken when the machine is again started.

25 One of the several objects of the present invention is to provide for the lubrication of the needle of a sewing machine so that the needle is at all times adequately lubricated.

One of the several features of the present invention resides in a needle lubricating device for 30 a sewing machine having means to supply lubricant to the needle and means to control the supply so that oil is delivered to the needle when the machine stops and starts and at predetermined intervals during the operation of the machine.

The above and other objects and the several features of the invention will become apparent 35 from a consideration of the following description given by way of example of a preferred form of 40 needle oiling mechanism according to the invention.

In the accompanying drawings:—Figure 1 is a 45 side elevation of part of a sewing machine illustrating the said preferred form of needle oiling mechanism; Figure 2 is a side elevation of the 50 said needle oiling mechanism to a larger scale than in Figure 1 and with some of the parts in a different position; Figure 3 is a rear elevation 55 of the said needle oiling mechanism; and Figure 4 is a detail sectional view of the pump.

The said preferred form of needle oiling mechanism will be illustratively described as being applied to the needle oiling device disclosed in the 55 specification of British Letters Patent No. 410,497.

The preferred form of mechanism includes a pump, indicated at 1, similar to that described in the latter specification. This pump comprises a cylindrical and relatively small oil chamber which is supported on a vertical stem 2 passing axially through the chamber and secured to a fixed part 4 of the machine. The said stem has a bore 6 formed axially in it and its upper end projects just beyond the upper end of the oil chamber. The lower end of the stem projects downwardly below the bottom of the oil chamber for some distance and the diameter of the bore in the stem below the bottom of the oil chamber is relatively small (i. e., is approximately one third of that of the stem) while the diameter of the bore in 10 the stem just above the bottom of the oil chamber is somewhat larger. A plunger 3 passes downwardly into the bore in the stem and is of a diameter equal to that of the relatively small bore in the lower end of the stem, the lower end of the plunger entering into the relatively small bore. 20 A recess 10 is provided in the upper end of the stem and a spring 12 bearing at its lower end against the bottom of the recess and at its upper end against the underside of a head 14 formed on 25 the top of the plunger tends to lift the plunger upwardly.

A hole 16 is bored radially in the wall of the stem just above the bottom of the oil chamber. A duct 18 is drilled axially along the plunger for 30 a short way from its lower end and communicates by a radial hole 20 drilled in the plunger with the hole 16 in the stem when the plunger is lifted by the spring 12 aforementioned. The bore in the stem narrows down to a neck 22 some 35 distance below the lower end of the plunger and a ball 24 is urged upwardly against the underside of the neck to close the bore by a spring 26 which is supported by the upper end of a pipe 28 which is fitted into the lower end of the bore. 40 Thus, when the plunger is in the position shown in Figure 4, oil may flow from the container through the holes 16 and 20 through the duct 18 in the lower end of the plunger into the narrow bore in the stem 2 below the plunger, which 45 bore is normally closed by the said ball 24. By pressing upon the upper end of the plunger 3, the latter can be urged downwardly along the stem and, when it has been lowered so far that the radial hole 20 in the lower end of the plunger 50 no longer communicates with the hole 16, continued downward movement of the plunger will force oil out of the narrow bore below it and past the ball 24, the latter yielding downwardly against its spring. 55

The pipe 28 has a fine bore and serves to conduct the oil forced out of the stem by the plunger on to a needle guide which surrounds the shank of the needle to support it against 5 lateral bending as it pierces the work. The needle guide is given rocking movements along the needle to support the latter as close to the work as possible and is brought to its highest and rearmost position when the machine stops, 10 as more particularly described in the specification of British Patent No. 410,497 above referred to. The needle guide has an opening through it containing a felt pad through which the oil dropped on to it from the pipe 28 may seep on 15 to the needle.

The plunger is at its upper end pivotally connected to the lower end of an upwardly extending toggle link 5. The upper end of the plunger 3 has a screw threaded connection with a pin 7 20 on which the link 5 is pivoted so that the plunger may be adjusted vertically to vary the amount of oil supplied by the pump at each depression of the plunger. The plunger is secured in the pin 7 by a screw 9. The upper end of the link 5 25 is pivotally connected to a second upwardly extending toggle link 11. The upper end of the toggle link 11 is pivoted at 13 on a bracket 15 secured to the frame of the machine. As the toggle is straightened the plunger 3 of the pump 30 1 is depressed to supply a drop of oil to the needle and, when the toggle is broken to one side or the other of the plane which passes through the pivots of the toggle, when the toggle is straightened, the pump plunger is raised. The upper link 11 of the toggle has an arm 17 in 35 which is adjustably secured a screw 19, held in adjusted position by a lock-nut 21. The screw 19 is engaged by one arm of a lever 23 pivoted at 25 to the machine frame. The other arm of the lever 23 is connected by a rod 21 to an arm 29 40 secured on a rock shaft 31.

The shaft 31 is rocked in one direction when the machine starts and in the opposite direction when the machine stops, as described in the 45 specification of British Patent No. 410,497. Movement of the lever 23, by its connection to the rock-shaft 31 or by a spring 33, in either direction, causes the toggle to straighten and to move to the opposite side of the aforesaid plane 50 so that each time the machine is started and stopped, the plunger 3 of the oil pump 1 is actuated to supply oil to the needle.

When the joint of the toggle is on that side of the aforesaid plane to which it moves when 55 the machine is started it, as shown in Figure 2, is engaged by one arm of a cam lever 35 pivoted at 37 on the aforesaid bracket 15. The other arm of the cam lever carries a cam roll 39 which is held, by the spring 33 connected to the cam lever 35 and to the arm 17, against a cam 41 60 secured on a shaft 43, rotatably mounted in said bracket 15 and rotated by suitable means from the driving shaft of the machine. Conveniently the shaft 43 is connected by spiral gearing indicated at 45 and 47 to a shaft 49 which in the 65 machine disclosed in the specification of British Patent No. 410,463, drives the shuttle of the machine and is referred to as 45 therein. The action of the cam 41 on the cam lever 35 causes 70 the toggle to be straightened or substantially straightened and the pump plunger 3 to be depressed sufficiently to supply a drop of oil to the needle. During the straightening of the toggle by the cam 41, the screw 19 in the arm 17 75 moves away from the lever 23.

The spring 33 which is connected to the cam lever 35 and the arm 17 of the upper link 11 of the toggle, besides holding the cam roll 39 on the cam lever 35 against its cam 41, also holds the link 11 of the toggle against the cam lever. 5

The cam 41 is formed so that it actuates the cam lever 35 four times during each revolution of the cam and is preferably rotated at such a speed that the cam lever is actuated to supply oil to the needle during the operation of the machine once in about every fifty cycles of the machine, i. e., about fifty stitches are formed between successive actuations of the pump plunger by the cam during the operation of the machine. If, for example, the machine is caused to operate at one thousand revolutions per minute the cam will rotate at five revolutions per minute. The shape of the cam may be such, however, as to cause a drop of oil to be supplied to the needle after any desired number of stitches have been 20 formed.

From what has been said above, it will be understood that on the starting of the machine a drop of oil is automatically supplied to the needle and when, during the operation of the machine, the cam lever 35 is first actuated by the cam 41, the pump plunger 3 is depressed to supply a further drop of oil to the needle. The number of cycles of the machine and the number of stitches formed after the machine starts, 30 and before the latter drop of oil is supplied to the needle will, of course, depend upon the relative stopping position of the cam 41 and the cam roll 39 on the cam lever 35. After the first drop of oil has been supplied by actuation of the cam lever 35, drops of oil are supplied in this manner after about every fifty stitches have been formed and, when the machine comes to rest, a drop of oil is supplied to the needle by the movement of the toggle across the plane 40 aforesaid, as hereinbefore described.

While the device just described in detail has been considered as applied to a needle oiling device in which the oil is dropped on to the needle guide or on to a pad in the needle guide and by the latter applied to the needle, this is obviously not a necessary condition. For instance, the device described in detail above may be applied to a needle oiling device which, by means of a brush (to which the oil is supplied) applies the oil to the needle between its point and the needle guide as, for example, is disclosed in the application of Otto F. Hoppe Serial No. 717,212, filed March 24, 1934.

The nature and scope of the invention having 55 been indicated, and a construction embodying the several features of the invention having been described, what is claimed is:

1. In a sewing machine, the combination with a needle, of a needle lubricating mechanism comprising a reservoir for lubricating material, means comprising a conduit for conducting lubricant from the reservoir to the needle, and means driven from the machine operating periodically after a plurality of stitch forming cycles and 65 during the continued operation of the machine in sewing a seam to supply lubricant from the reservoir to the conduit.

2. In a sewing machine, the combination with a needle, of a needle lubricating mechanism comprising a reservoir for lubricating material, means comprising a conduit for conducting lubricant from the reservoir to the needle, means operating upon starting the machine for supplying lubricant from the reservoir to the conduit, and 75

- means operating periodically after a plurality of stitch forming cycles and during the continued operation of the machine in sewing a seam to lubricant from the reservoir to the conduit.
- 5 3. In a sewing machine, the combination with a needle, of a needle lubricating mechanism comprising a reservoir for lubricating material, means comprising a conduit for conducting lubricant from the reservoir to the needle, means operating upon starting and stopping the machine for supplying lubricant from the reservoir to the conduit, and means operating periodically after a plurality of stitch forming cycles to supply lubricant from the reservoir to the conduit.
- 10 4. In a sewing machine, the combination with a needle, of a needle lubricating mechanism comprising a reservoir for lubricating material, means comprising a conduit for conducting lubricant from the reservoir to the needle, means comprising a plunger for supplying lubricant from the reservoir to the conduit, and a cam and suitable connections for actuating said plunger periodically after a plurality of stitch forming cycles.
- 15 5. In a sewing machine, the combination with a needle, of a needle lubricating mechanism com-

prising a reservoir for lubricating material, means comprising a conduit for conducting lubricant from the reservoir to the needle, means comprising a plunger for supplying lubricant from the reservoir to the conduit, connections actuated 5 in starting and stopping the machine for actuating said plunger, and a cam acting through said connections to actuate the plunger periodically after a plurality of stitch forming cycles.

6. In a sewing machine, the combination with 10 a needle, of a needle lubricating mechanism comprising a reservoir for lubricating material, means comprising a conduit for conducting lubricant from the reservoir to the needle, means comprising a plunger for supplying lubricant from 15 the reservoir to the conduit, toggle links connected to the plunger, means actuated in starting the machine for moving the toggle links in one direction to actuate the plunger, and in stopping the machine, to move the toggle links in the 20 opposite direction to again actuate the plunger, and a cam arranged to move the toggle links to actuate the plunger periodically after a plurality of stitch forming cycles.

CERTIFICATE OF CORRECTION.

Patent No. 2,051,250.

August 18, 1936.

HAROLD ERNEST ELLIOTT.

It is hereby certified that error appears in the printed specification of the above numbered patent requiring correction as follows: Page 3, first column, line 3, claim 2, after the word "to" insert supply; and that the said Letters Patent should be read with this correction therein that the same may conform to the record of the case in the Patent Office.

Signed and sealed this 12th day of October, A. D. 1937.

Henry Van Arsdale.

Acting Commissioner of Patents.
